UNITED STATES PATENT OFFICE.

EMIL O. H. POEPPEL, OF CHICAGO, ILLINOIS.

METHOD OF ASSEMBLING RADIATOR RELIEF VALVES.

Application filed November 11, 1926. Serial No. 147,719.

This invention relates to a relief valve for use on a steam heating system radiator.

The main objects of this invention are to provide a structure in which the valve actuating mechanism is assembled and supported on a unitary housing with the valve spaced from its valve seat an exact predetermined amount, this adjustment of the valve being independent of the relation in which the housing and base members are assembled.

Heretofore in the manufacture of this form of relief valve, it has been customary to make the article with two principal parts to the body, that is, a cup-shaped base member having a threaded nipple secured thereto for attaching to a radiator, and an elongated dome-shaped tubular housing suitably mounted on the base member. The dome-shaped housing member is provided with an outlet having a valve seat, and with a valve actuating mechanism supported on the base member. This form of structure necessitated an adjustment of the valve clearance after the base and housing member had been assembled together, due to variations in the length of the housing body and in the positioning of the housing member on to the base member.

An illustrative embodiment of this invention is shown in the accompanying drawings, in which:—

Fig. 1 is a vertical sectional elevation of the dome-shaped housing body with the dust cap screwed onto the tubular neck.

Fig. 2 is a vertical elevation partly in section of the thermostatic valve body and needle valve carried thereby.

Fig. 3 is an elevation of the supporting spider which retains the thermostatic valve in the housing body.

Fig. 4 is an elevation partly in section of the base member, which carries the housing body and which is adapted to be secured to a radiator.

Fig. 5 is a view in perspective of the spacing member used in assembling the valve parts.

Fig. 6 is a plan view of the spider shown in Fig. 3.

Fig. 7 is a vertical elevation partly in section of the housing body, with the thermostatic valve and supporting spider assembled therein with the spacing member in position between the spider and the diaphragm of the valve body.

Fig. 8 is a vertical elevation, partly in section, of the completely assembled relief valve in its cold position, showing the needle valve spaced away from its valve seat. 60

Fig. 9 is a vertical elevation, partly in section, of the same with the valve in hot position, showing the needle valve closed on its valve seat.

In the construction shown in the drawings a thin sheet metal cup-shaped base member 1 interiorly threaded at its rim 2 is provided with a short pipe nipple 3 swaged or otherwise suitably secured thereto, the nipple 3 being exteriorly threaded at its outer end for the purpose of attaching to a radiator. 65

A vertically disposed elongated tubular housing member 4 is exteriorly threaded at its lower end 5 so as to be mounted on the base member 1 by being screwed thereinto. The upper end of housing 4 is dome-shaped and carries a vertical projecting externally threaded tubular neck 6 swaged thereto, providing an outlet for air and steam. The upper portion 7 of the tubular neck's bore is diametrically less than the lower portion forming a valve seat 8. 75

An interiorly threaded dust cap 9 is screwed to the neck 6 and is provided with ports 10 and 11 adjacent the outer edge of the top. These portions 10 and 11 do not register with the outlet 7 in the neck and any dust that may enter the ports is thus deflected from directly entering the opening 7. The walls of the cap 9 are of greater length than the neck 6 so that when the cap is screwed down on to the neck, the top of the cap is spaced away from the top of the neck forming a chamber 12 as shown in 90 Fig. 1. 95

The opening 7 is controlled by a needle valve 13 for coacting with the valve seat 8. The valve 13 is mounted coaxially on the dome-shaped end 14 of an inverted cup-shaped valve body 15, the lower end of which is hermetically sealed by a thermostatic diaphragm 16. The valve body 15 contains a small amount of gas-forming liquid, such as alcohol, which expands rapidly when subjected to a slight amount of heat. When the diaphragm 16 is cold or in normal position, it is bowed inwardly toward the body 15, that is, concave, and when heated is adapted to bow outwardly, that is, be convex with respect to the valve body. The valve body 15 is of such diam- 100

105

110

eter that it is readily slidably and movable within the housing 4 and is supported and retained therein by a spider or supporting bridge 17, soldered or otherwise suitably secured to the interior walls of the housing member 4. The center portion of the spider 17 is bowed toward the valve body and bears against the diaphragm 16. The spider 17 is secured to the housing in such position that the needle valve 13 will be spaced away from the valve seat 8 a distance substantially equal to the distance traveled by the center portion of the diaphragm 16 when said diaphragm moves from a concave to a convex curvature due to expansion of the gas in the valve body 15.

This proper spacing of the valve is secured by the use of an L-shaped spacer 18, the short leg 19 of which is placed between the spider 17 and the diaphragm 16 during the assembly of the unit, with the diaphragm 16 in concave or cold position and with the needle valve 13 resting on its seat 8. After this spider 17 has been soldered in place, spacer 18 is removed from its position between the spider and diaphragm, thus allowing the valve body 15 carrying the needle valve 13 to be spaced away from its valve seat a distance equal to the thickness of the leg 19. The operating part and the manner of assembling them makes the spacing of the needle valve from its seat a matter entirely independent of the depth to which the housing 4 is screwed in its base 1.

In the operation of the device, the valve in its normal cold position is spaced from

its seat and when the steam in the radiator is turned on, the cold air in the radiator will pass out through the outlet opening 7 and ports 10 and 11 of cap 9. When the air has all been forced out of the radiator by incoming steam and the steam begins to pass out around the valve body 15, it heats and expands the gas in the valve body 15 and forces the diaphragm 16 from a convex to a concave position. This movement of the diaphragm which rests on and bears against spider 17, raises the valve body 15 and needle valve 13 upwardly in the housing 4, causing the needle valve 13 to bear against its valve seat 8, thereby closing the outlet 7.

Although but one specific embodiment of this invention has been herein shown and described, it will be understood that numerous details of the construction shown may be altered or omitted without departing from the spirit of this invention as defined by the following claim:

The method of assembling a radiator relief valve which comprises the placing of a valve and a valve actuating means in a housing body having a valve seat with the valve closed on said seat, inserting a supporting spider in said housing with a spacing member between said spider and said valve actuating means, securing said spider in such a position, and then removing said spacing member.

Signed at Chicago this 5th day of November, 1926.

EMIL O. H. POEPPEL.
